UNITED STATES PATENT OFFICE.

JOHN BEST, OF PATERSON, NEW JERSEY.

DESIGN FOR A BANNERET.

SPECIFICATION forming part of Design No. 22,983, dated December 26, 1893.

Application filed November 2, 1893. Serial No. 489,881. Term of patent 3½ years.

To all whom it may concern:

Be it known that I, JOHN BEST, a citizen of the United States, residing at Paterson, in the county of Passaic and State of New Jersey, have invented and produced a new and original Design for Bannerets Commemorative of the Late Columbian Exposition; and I do declare the following to be a full, clear, and exact description of the same, reference being 5 to the accompanying drawings, forming a part thereof.

The object of my design is to produce an ornamental banneret having thereon features commemorative of the Columbian Exposition, 10 woven therein or thereon or otherwise placed thereon.

The leading or characteristic features which constitute my design, are, the representation of the landing of Columbus, a representation 15 of the Eastern Hemisphere and the Western Hemisphere above the same; and below

said representation of landing of Columbus is a view of the New York harbor and Statue of Liberty, and the Administration building; below which is a view of the Hudson river, 25 with steamboats, and on the shore a locomotive drawing a train of cars, on the bank of the river sheaves of wheat or rye and pieces of machinery, representing manufacture, commerce and agriculture. An American flag 30 hanging in graceful folds forms the background for the picture, and an American eagle surmounts the whole, holding the flag staff in his talons.

With this description, what I claim is— 35
The design for a banneret substantially as herein shown and described.

JOHN BEST.
